UNITED STATES PATENT OFFICE

167,979

CLOTHESPIN

James M. Harlan, Lawrenceville, Ill.

Application June 2, 1952, Serial No. 19,994

Term of patent 14 years

(Cl. D17—6)

To all whom it may concern:

Be it known that I, James M. Harlan, a citizen of the United States, residing at Lawrenceville, in the county of Lawrence and State of Illinois, have invented a new, original, and ornamental Design for a Clothespin, of which the following is a specification, reference being had to the accompanying drawing, forming part thereof.

I claim:

The ornamental design for a clothespin, as shown.

JAMES M. HARLAN.
